UNITED STATES PATENT OFFICE.

JOSEPH CARL ELGER, OF PITTSFIELD, MASSACHUSETTS.

AEROPLANE.

Application filed December 20, 1927. Serial No. 241,294.

This invention relates to aeroplanes and has for its object to provide a construction which will facilitate the forward propulsion thereof, eliminate the tendency of the aero- 5 plane to tilt sideways; aid in retaining the equilibrium when the driving power ceases, also facilitate gliding or soaring in the air and assure perfectly safe landing.

Another object is to provide a construction which will simplify and reduce the cost 10 of manufacture of an aeroplane.

With this and other objects in view my invention consists of the novel construction, combination and arrangement of parts as 15 will be hereinafter more fully described in the appended claims.

In the accompanying drawing which forms part of this specification and in which similar reference characters denote corre- 20 sponding parts, Fig. 1 is a side elevation of my aeroplane; Fig. 2 a bottom plan view thereof; Fig. 2^a a cross sectional view of the fuselage; Fig. 3 a longitudinal section on line 3—3 of Fig. 2, of the aeroplane and Fig. 25 4 a cross section thereof on line 4—4 of Fig. 3.

The aeroplane according to this invention comprises a dart shaped body 10 which may be made of a flat sheet of metal of substan- 30 tially rectangular shape having a pointed edge at one end and bent alternately up and down transversely as best shown diagram- matically in Fig. 2^a, to form at suitable in- 35 tervals a plurality of longitudinal parallel downwardly extending flutes 11, 12 and 13 closed at their sides and bottoms, the spaces 40 14 between the individual flutes forming tunnels or channels. One of the flutes, 12, extends along the central longitudinal line of the flat surface and the others 11, 13 are 45 symmetrically distributed on both sides of said central flute. Each flute has vertical side walls and rounded bottoms 11^a, 12^a, 13^a. The tops 15 of the channels 14 are flat. The 50 flutes starting from the pointed edge, where they are the shallowest, gradually increase in depth toward the rear end of the surface and there are closed by slanting walls 11^b, 12^b, 13^b which rise from the bottoms of the 55 flutes at an angle of approximately 45° to the flat surface.

The central flute 12 is adapted to consti- 55 tute a compartment for the crew, passengers, freight etc., and is made the widest and deepest, while the lateral flutes do not extend as far down and may be narrower, as

shown. The central flute is provided on its top with a covering or hood 16 substantially of the shape shown, which projects above the flat surface from the front edge of the 60 plane to an intermediate point thereof and at its rear slants downwardly as at 16' and is extended to the rear end of the top as at 16² to form the top for the deepest part 65 of the flute 12. The side and front walls of the hood may be provided with windows 15 and a cockpit 17 or the like.

The flanking parts 15' of the flat surface, as well as the lateral flutes and channels serve to stabilize the plane and prevent it 70 from tipping sidewise during flight, raise it when propelled forwardly and keep up the tendency of the plane to move forwardly when the driving power ceases. The rear- 75 wardly slanting bottom of the channel owing to the pressure of the air from below against the same have the effect of raising the plane while in flight and permitting it to glide when the motive power is discontinued.

The flutes 11, 13 when closed on top as shown may be filled with air or gas rendering the plane buoyant. Instead of closing 80 said flutes, there may be separate tanks (not shown) mounted therein to contain a medi- um rendering the ship buoyant.

On top of the gondola or hood and at other places of the flat surface funnel shaped members or sails 18 may be provided. The latter have their openings directed toward 90 their rear and serve to aid in the propulsion of the plane when travelling in the direction of the wind. Rudders 19, 19' may advantageously be accommodated in the channels 14 and below the flanking surfaces. 20 de- 95 notes the usual wings or supporting planes.

What I claim is:

1. In an aeroplane, a fuselage or body formed of a flat piece of rigid material pro- 100 vided with a number of longitudinally ex- tending tubular flutes spaced apart and pro- jecting below the surface, the spaces between said flutes forming tunnels or channels, said flutes being made to gradually increase in depth toward the rear, the central flute be- 105 ing provided with a hood and serving as a compartment or gondola, while the lateral flutes and channels serve to stabilize the plane in flight, preventing lateral tipping, assuring safe landing and promoting the 110 forward propulsion of the aeroplane as well as gliding, the partition of the air below

the plane surface by single arrowlike walls or by hollow tubes as shown in the drawings.

2. In an aeroplane, a fuselage or body formed with a number of longitudinal parallel flutes spaced apart and projecting in a rearwardly inclined position below the surface thereof, the spaces between said flutes

forming tunnels or channels of which the central one serves as a compartment for the crew and the lateral ones serve to stabilize the plane in flight. ¹⁰

In testimony whereof I affix my signature.

JOSEPH CARL ELGER.
